UNITED STATES PATENT OFFICE.

COLUMBUS K. LASSITER, OF SCHENECTADY, NEW YORK

BOLT-CUTTING MACHINE.

No. 829,972.

Specification of Letters Patent.

Patented Sept. 4, 1906.

Application filed December 10, 1903. Serial No. 184,657.

To all whom it may concern:

Be it known that I, COLUMBUS K. LASSITER, a citizen of the United States, residing at Schenectady, in the county of Schenectady and State of New York, have invented new and useful Improvements in Bolt-Cutting Machines, of which the following is a specification.

This invention relates to mechanism for forming stay-bolts and the like; and the primary object of the same is to simplify and improve the organization of devices of this class so that they will automatically thread the terminals and concave the intermediate portions of stay or other bolts at any required or determined depression.

The mechanism embodying the features of the invention may be used in connection or operative relation to machines for preparing bolt-blanks, so as to provide convenient manipulation in the steps of completion of bolts of the class set forth.

The present machine essentially embodies guide means, a carriage movable on said means, and thread-cutting devices and a concaving-tool supported by said carriage.

The invention also consists in the construction and arrangement of the parts, which will be hereinafter more fully set forth.

30 In the drawings, Figure 1 is a front elevation of a machine embodying the features of the invention and shown broken in parts. Fig. 2 is a transverse vertical section through the machine on line 2-2, Fig. 1. Fig. 3 is a top plan view of the tool-carriage, shown broken away in part, and the guides and a part of the operating means therefor in horizontal section. Fig. 4 is a horizontal section through the carriage shown by Fig. 3 with a part of

40 the tool holding and guiding means removed. Fig. 5 is a transverse vertical section through the tool-holding carriage, showing portions of devices co-operating therewith in elevation. Fig. 6 is a longitudinal vertical section on the line 6-6, Fig. 3. Fig. 7 is a detail top plan view of a bracket for the upper extremity of a tool-controller. Fig. 8 is a side elevation of the bracket shown by Fig. 7. Fig. 9 is a top plan view of the lower bracket for the tool-

45 controller. Fig. 10 is a side elevation of the bracket shown by Fig. 9. Fig. 11 is a side elevation of the tool-controller. Figs. 12, 13, and 14 are detail views of the tool shifting and guiding head which is operated in one 55 direction by the tool-controller.

Similar numerals of reference are em-

ployed to indicate corresponding parts in the several views.

The numeral 1 designates a base of suitable dimensions, on which is supported a bed 2, 60 having a chamber 3 opening through the bottom thereof for convenience in assembling operating mechanism, which will be more fully hereinafter set forth. On the top of the bed 2 is an oil-receiving hopper or fixed 65 receptacle 4, having an outlet-pipe 5 leading therefrom downwardly to a lower oil-tank 6.

Rising from opposite portions of the bed 2 are uprights 7, having mounted on their upper ends an oil-distributing tank 8, from 70 which extends an oil-supply pipe 9 down to the lower extremity of a pump 10 of suitable construction, the pump piston-rod 11 projecting upwardly therefrom and movably attached to an eccentric-arm 12 of an eccentric 75 13 on a stub-shaft 14, held by a bracket 15 on one end of the bed 2, the said shaft also having a driving-pulley 16 fixed thereto, surrounded by a belt 17, engaging a belt wheel or pulley 18 on a driving-shaft 19, which may 80 be operated from suitable line-shafting within a shop and having a band wheel or pulley 20 thereon to receive a connecting-belt. The shaft 19 has bearing in the upper end of a standard 21 and also in a portion of the 85 base 1, as shown by Fig. 2, the extremity of the shaft 19 that extends into the base engaging a suitable bearing in a hanger 22. Secured on the inner extremity of the shaft 19 is a bevel-pinion 23, which is held in continual mesh with a horizontally-disposed bevel-wheel 24, held suspended within the upper part of the base 1 by a spindle 25, rotatable in a sleeve 26, secured at its upper extremity on the top of a boss 27, rising from 90 the center of the bed 2 within the confines of the receptacle or hopper. On the upper end of the shaft 25 is a head 28 with a substantially convex upper surface, in the center of which is formed an angular opening 29, communicating with a horizontal bore 30, opening at both ends at diametrically opposite points of the head. Between the spindle and head, at the lower portion of the latter or where the formation of the spindle begins, a 95 shoulder 31 is formed and bears on the upper end of the sleeve 26 to durably sustain the weight of the spindle and gear-wheel 24. The lower end of the spindle close to the gear-wheel 24 has a stop-collar 32 thereon, which is snugly engaged by the lower end of the said sleeve, and by thus confining the 100

105 gear-wheel 24 has a stop-collar 32 thereon, which is snugly engaged by the lower end of the said sleeve, and by thus confining the 110

spindle at opposite portions between the head 28 and the collar 32 it is prevented from having movement in its bearing means, and the gear 24 is always held in continual mesh with the pinion 23. The upper extremity of the spindle 25 has oppositely-projecting horizontally-disposed fastening lugs or ears 33, which bear upon and are secured to the boss 27, and over the lower part of the head 28 and the upper extremity of the sleeve 26 a hood 34 is secured to prevent the collection of chips or metal particles around the joint between the upper extremity of the sleeve 26 and the head and its spindle, said head extending through the top of the hood and having a flange 35 bearing on the latter. The opening 30 through the head is to facilitate the removal of small particles of metal that may fall on the top of the head and into the opening or socket 29 when the bolt is released from the latter.

Rising from the bed between the uprights 7 and attached to the bottom of the oil-distributing tank 8 are a pair of guide-rods 36, on which is slidably mounted a tool-holding carriage 37. Secured to the carriage 37 and movably extending upwardly through the bottom of the tank 8 and tubular guides 38 said bottom are operating-rods connected at their upper ends by a cross-head 40, having a central seat 41; to which the one end of an operating-belt 42 is attached. This belt 42 is passed upwardly over and extends downwardly from a belt-wheel 43, secured on a shaft 44, held by hanger means 45 and also having thereon a band-wheel 46. The belt 42 extends downwardly within convenient reaching distance at one side of the machine and is normally in slack engagement with the band-wheel 43. The shaft 44 is continually rotated, and in order to make the belt 42 effective to elevate the carriage 37 the operator draws downwardly on and causes the said belt 42 to move over the belt-wheel 43. This arrangement facilitates the elevation of the carriage 37 without imposing the weight thereof on the operator. The carriage 37 has considerable weight, especially when the tools and co-operating devices for the latter are disposed therein, and after such carriage has been raised to operate on a bolt to be treated or threaded and shaped, as will be more fully hereinafter explained, the said carriage is released and allowed to have a gravitating feed in proportion to the work completed or the regular operation of the cutting devices carried by said carriage.

Depending from the oil-distributing tank 8 and extending into the oil-receiving hopper 4 is an overflow-pipe 47, which projects far enough upwardly into the tank 8 to prevent the oil pumped thereinto from rising above a certain level. The oil has outlet from the bottom of the distributing-tank 8 through a

valved feeding-pipe 48; depending therefrom and having its lower outlet end disposed in vertical alinement over the carriage in such position with relation to the latter as to deposit the oil on the bolt threaded and shaped. The oil flowing down over the bolt and passing through the carriage 37 enters the hopper 4 and from the latter runs into the lower tank 6, from whence it is drawn through a pipe 49, connecting with the upper extremity of the pump 10 at a suitable point. By this means the oil can be repeatedly used with a great saving and economy in the art of bolt cutting or preparation, especially where a large number of machines are used in a plant.

The carriage 37 is clearly shown on an enlarged scale by Figs. 3, 4, 5, and 6 and consists of an intermediate body 50, having diagonally-opposed tubular guides 51, movable on the guide-rods 36. Extending through the body 50 and opening outwardly at opposite ends thereof is an adjusting-block channel or seat 52, having adjusting blocks or carriers 53 shiftably mounted therein and movable outwardly from and inwardly toward each other. The channel or seat 52, as shown by Fig. 5, is of dovetail contour, with the reduced part thereof opening through the bottom of the body 50 for convenience in applying screw-thread-cutting devices thereto. The screw-thread-cutting devices have shanks 54 with outer shoulders 55 and inner heads 56, so constructed as to be effective in cutting threads and clearing the chips away from the threads as cut. The cutting devices are dovetail in cross-sectional contour and removably fitted in dovetail seats 57, formed in the lower portions of the blocks 53, each cutting device being less in width than its seat and having interposed between one side thereof and the adjacent side wall of the seat a securing-wedge 58, held in immovable position by set-screws 59, which are operative from the under side of the carriage to loosen or tighten the wedges in adjusting the screw-thread-cutting devices. The screw-thread-cutting devices have an adjustment independent of the adjustment or movement of the blocks 53, in which they are disposed, through the medium of elongated screws or screw-threaded rods 60, having angular heads 61 projecting outwardly beyond the outer ends of the blocks 53. The inner ends of the screws or rods 60 bear against the shoulders 55, and by this means the screw-thread-cutting devices may be projected inwardly with relation to the center of the carriage to regulate the dimensions of the threads to be cut.

The blocks 53 are shiftable through the medium of vertically-disposed cam devices engaging the outer extremities thereof and consisting of rods 62, having intermediate cam enlargements 63, the upper ends of the rods 62 respectively extending through the

inner ends of actuating-levers 64 and 65, the lever 65 being lengthened to serve as a hand-lever and connected to the terminal of the lever 64 by a link-bar 66, as clearly shown by Figs. 3, 5, and 6. The ends of the rods 62, extending through the inner ends of the levers 64, are angular in cross-section, as at 67, (see Figs. 3 and 6,) to insure their operation by movement of the levers attached thereto and primarily actuated by the hand-lever 65. The upper portions of the rods 62 are rotatable in the opposite reduced ends of a top bearing-plate 68, having a central enlargement 69, with an opening 70 therethrough to fit over a center head 71, having an upwardly-flared opening 72 therethrough to facilitate the insertion of a bolt through the center of the carriage and feeding of the oil to the bolt as it is cut or shaped by the mechanism for this purpose. The bearing-plate 68 also serves to hold the cam devices up in position when the upper angular ends of the rods 62 are engaged by the lever 64. The said bearing-plate has pivotal movement on the head 71, and the latter is shouldered at an intermediate point and rests on the top of the body 50 adjacent to an opening 73, formed in said body, to receive the lower portion of the head, the latter extending down to and engaging the blocks 53, as clearly shown by Figs. 5 and 6. The lower extremities of the rods 62 are rotatably mounted in the intermediate portions of bearings 74, terminally connected to move in unison by rods 75, and the lower end of each rod is reduced and screw-threaded, as at 76, to receive a nut 77, which is turned up against the bottom of the bearing 74, with which it co-operates, to hold the cam device in place.

When the hand-lever 65 is pulled outwardly from the carriage in the position shown by Fig. 3, the cam enlargement 63 will be thrown inwardly and force the blocks 53 in a similar direction or toward the center of the carriage to bring the heads 56 of the thread-cutting devices into operative engagement with the bolt to be threaded thereby, and when said hand-lever is so operated the bearing-plate 68 will occupy the position shown by Fig. 3. When it is desired to throw out the blocks 53, the hand-lever 65 is moved inwardly toward the carriage, throwing the cam enlargements in outward position by movements thereof in opposite directions. It will be understood that the cam enlargements could be so arranged, without in the least departing from the spirit of the invention, that the movements of the levers in performing the operations just set forth could be reversed. The advantage of this movement of the blocks 53 and the thread-cutting devices carried thereby is that the carriage may be freely moved over a bolt after the latter has been placed in position in the machine to a point at the upper extrem-

ity of said bolt, where the threads are first cut, and, further, in some instances to facilitate the removal of a bolt which has been threaded without injuring the threads thereof. By having the bearing-plate 68 pivotally mounted on the carriage it is permitted to give way or move proportionately to the change of position of the cam enlargements 63 without losing the advantageous effect of having the cam devices continually remain connected to the said bearing-plate. The plate 68 also limits the outward and inward movements of the blocks 53 through the cam devices carried by the said plate and co-operating with the blocks, and, moreover, the ends of the plate by forming bearings for the upper ends of the rods 62 render the application of the levers 64 and 65 practical, as the plate 68 serves as a yoke and insures a positive operation of the blocks 53. If the levers 64 and 65 were directly connected to the rods 62 and the plate 68 were absent, the movements of the blocks 53 would be unreliable and impositive. It will be observed that the cams 63 are cross-sectionally of circular form and turn in corresponding openings in the blocks 53, while the trunnions of said cams—i. e., the upper and lower ends of the rods 62—are offset from the axis thereof. Consequently as the cams turn in one direction or the other to slide the blocks 53 in or out the trunnions or rod ends must shift their position transversely of the blocks in order to allow the cams to operate the blocks without exerting lateral pressure on the latter. This shifting movement of the trunnions is attained by reason of the fact that the plate 68 and bearings 74, in which said trunnions are journaled, are free to swing laterally to permit such shifting movement. The carriage also carries a concaving-tool arranged in diagonal position therein and movable through an opening 78, extending horizontally from the outer side of the body inwardly to the central bolt-opening through the latter at an elevation slightly above the position of the thread-cutting devices 54. This concaved cutting-tool consists of a cylindrical shank 79, having an inner cutting-head 80, the tool being of such length as to permit it to be fed inwardly a distance to cut the maximum depression of the concavity without disengaging the shank 79 from the devices for controlling the operation of the tool.

The concaved cutting-tool is held in a head 81 on one side of the carriage, the said head having an outer offset 82 at one side of the center with a slot 83 extending vertically therethrough. The slot 83 communicates with a vertical opening 84, also completely passing through the head from the top to the bottom, and in one side wall of the opening 84 is a longitudinal groove 85, in which slidably fits a feather or spline 86 on the outer terminal of a laterally-projecting feeding-

4

arm 87 of a feeding-head 88, secured on the shank 79 by a set-screw or analogous device 89. The arm 87 at its outer side has opposite reversely-inclined faces 90 to form a reduced bearing edge 91 for a purpose which will be presently set forth. Between the inner end of the feeding-head 88 and the adjacent side portion of the body 50 of the carriage a coiled spring 92 surrounds the shank 79 and operates to throw the concaving-tool outwardly in normal position when the arm 87 is released from the maximum projection of a controller 93. This controller is held at opposite extremities in vertical position in the machine by an upper bracket 94, adjustably clamped on one of the guide-rods 36, and a lower bracket 95, secured to the machine-bed. The controller 93 consists of a flat bar disposed at an oblique angle to correspond to the position of the concaving-tool and having upper and lower screw-threaded extremities 96, which are each engaged by set-screws 97, respectively bearing against the upper and lower sides of the bracket through which the extremity extends. The object of the screw-threaded extremities 96 of the nuts engaging the same is to vertically move or shift the controller to bring a convex cam enlargement 98 at varying elevations in accordance with the length of the bolt or the part of the latter to be concaved in relation to the screw-threads to be formed at the upper and lower ends thereof. The controller 93 extends through the head 81 and engages the slot 83; said head 81 being freely slideable on the controller. When the cam enlargement 98 begins to contact with the bearing edge 91 of the arm 87, the feeder 88 is shifted inwardly and carries therewith the concaving-tool held thereby. The movement of the concaving-tool will be gradual as the carriage descends, and the concavity formed in the intermediate portion of the bolt will correspond in degree of depression precisely to the convexity of the enlargement 98. After the carriage has passed the cam enlargement 98 the concaving-tool will be forced outwardly in a normal position by the spring 92 to avoid interfering with the operation of the thread-cutting devices carried by the blocks 53.

It will be understood that the controller will be so adjusted that the vertical elevation of the cam enlargement 98 will not begin to operate on the feeder 88 until the screw-threads have been fully cut as desired at the upper end of the bolt, and the lower terminal of the said enlargement will be so positioned under the proper adjustment of the same as to cease to operate on the feeder and concaving-tool at a point where the upper limit of the threads on the lower end of the bolt begins.

For convenience in holding the controller in proper position in relation to the remaining mechanism the upper bracket 94 is con-

structed as shown by Figs. 7 and 8 and has a clamping-head 99 and an arm 100, with a terminal slot 101 extending outwardly therefrom at an angle. The lower bracket 95, as shown by Figs. 9 and 10, comprises a base 102, having a standard 103 rising therefrom, terminating in a horizontal arm 104 with an angular slot 105 opening outwardly therefrom, and when the brackets are properly applied the slots 101 and 105 in the respective brackets will be in vertical alignment for convenience in applying and removing the opposite nutted extremities of the controller and also in adjusting the latter.

The carriage 37 is disposed in diagonal relation over the bed of the machine to render the ends of the blocks 53 convenient for adjusting purposes and also make the head 81 and controller engaging the same readily accessible as well as to effectively position the thread-cutting devices and concaving-tool. The head 81 and feeder co-operating therewith may be termed a "tool-holder," and the object of the arm 87, having the spline 86 engaging the groove 85, is to hold the shank 79 against rotary movement and always retain the cutting-head 80 in proper position relatively to the bolt to be cut.

In the operation of the machine a bolt-blank having an angular stem is disposed in the head 28 with said stem resting in the angular socket 29. The carriage 37 is then elevated through the medium of the belt 42, the blocks 53 being first shifted to clear the thread-cutting heads 56 from engagement with the bolt during such upward movement of the carriage. The blocks 53 are then readjusted to bring the heads of the thread-cutting devices into engagement with the upper end of the bolt, and the carriage then gravitates over the upper extremity of the bolt while the latter is rapidly rotated through the mechanism for rotating the head 28, heretofore explained. The thread-cutting devices continue to operate on the upper extremity of the bolt until the upper terminal of the convex enlargement 98 of the controller is reached, when the concaving-tool will be brought into play and will fall behind the threaded cutting devices and continue to cut a concavity in the intermediate portion of the bolt until the carriage or the part thereof engaging the enlargement of the controller reaches the lower terminal of the latter, when the concaving-tool will be returned to outward normal position, while the thread-cutting devices will continue to form the threads on the lower end of the bolt. It is preferred to have the thread-cutting devices continuously thread the bolt throughout its length in order to preserve the lead of the thread and to project the concaving-tool behind such thread-cutting devices at the proper point and to operate for the proper period to cut away the thread formed upon the inter-

110
115
120
125
130

mediate portion of the bolt, thereby centrally reducing or concaving the bolt. In this operation the thread-cutting devices will continue to act, and the resultant product will be a bolt which is terminally threaded and intermediately reduced or concaved. The construction shown permits of a variation of this operation in which these steps may be successively performed—that is to say, the thread-cutting devices may first be thrown into operation to thread one end of the bolt, when they will be retracted and the concaving-tool will be projected to reduce the intermediate portion of the bolt, at the termination of the operation of which the thread-cutting devices will again be projected to thread the other end of the bolt. In either case, however, the work of threading and reducing the bolt is continuous and performed in a single operation. During this operation oil will be continually fed downwardly through the carriage and around the bolt. This operation can be readily and rapidly carried on in succession in each machine, and it is proposed to have a number of machines coupled for simultaneous operation from a single driving mechanism or line-shafting.

The machine may also be employed for forming bolts other than those known as "stay-bolts," and one main advantage of the machine is that either the thread-cutting devices can be used alone or the concaving-tool may operate solely, as may be desired. 35 When the threads are cut without concaving the bolt, the controller will be detached.

It will be understood that on the downward movement of the carriage its speed or descent will be regulated by the action of the 40 thread-cutters on the bolt-blank, thus gaging the carriage on its feed movement for the proper action of the turning-tool.

Having thus fully described the invention, what is claimed as new is—

45 1. In a machine of the class set forth, the combination of a rotatable bolt-holding means, a carriage movable in relation to said means, bolt-cutting devices carried by said carriage, and a controller passing through a 50 part of the carriage and adapted to dispose a part of the said cutting devices in operative position.

2. In a machine of the class set forth, the combination of bolt-holding means, a carriage automatically movable toward said bolt-holding means and having bolt-cutting devices therein, and a controller passing through a part of said carriage to automatically move a portion of the bolt-cutting 55 means into operative position.

3. In a machine of the class set forth, the combination of a rotating bolt-holding head, a carriage having movement toward said head, bolt-thread-cutting means in the carriage, a concaving-tool movably carried by

the carriage and having a feeder attached thereto, and a controller extending through the carriage and provided with an enlargement to engage said feeder.

4. In a machine of the class set forth, the combination of a rotatable bolt-holding means, a carriage having movement in relation to said means, thread-cutting devices mounted in said carriage, a concaving-tool also disposed in the carriage and having a feeder attached thereto, a controller having an enlargement to engage a portion of said feeder to move the concaving-tool inwardly, and means for automatically throwing the concaving-tool outwardly when released from the enlargement of the controller.

5. In a bolt-cutting machine, the combination of a rotatable bolt-holding means, a slideable carriage operating in relation to said means, thread-cutting mechanism held by 85 said carriage, a concaving-tool movably disposed in the carriage, a controller having an enlargement to operate the concaving-tool and project the latter inwardly between the initial and final operations of the thread-cutting mechanism, and means for automatically moving the concaving-tool outwardly when released by the controller.

6. In a machine of the class set forth, the combination of a rotatable bolt-holding 95 means, a carriage freely movable to and from said means, thread-cutting mechanism held by the carriage and having operating devices for throwing them inwardly and outwardly, and a concave-cutting tool also movably held 100 in the said carriage, and remaining inactive while the thread-cutting mechanism is in operation.

7. In a machine of the class set forth, the combination of bolt-holding means, a carriage movable toward and away from said means and having an opening therethrough and a head at one side, a feeder movable in the said head and provided with an arm slidably engaging a part of the latter, a movable 110 concaving-tool to which the feeder is attached, means between the feeder and a part of the carriage for returning the tool to normal position, and a controller having an enlargement to engage the arm of the feeder.

8. In a machine of the class set forth, the combination of bolt-holding means, a carriage movable toward and away from said means, and having an opening therethrough and also provided with a head at one side, the 120 said head having a groove in one wall of the same, a concaving-tool slidably mounted in the head and carriage, a feeder secured on the tool within the head and having an arm with a spline to engage the groove, means interposed between the feeder and the carriage for automatically throwing the tool outwardly, and a controller having an enlargement to bear against the arm to move the said tool inwardly.

9. In a machine of the class set forth, the combination of a bolt-holding means, a carriage movable toward and away from said means and having an opening therethrough and a head at one side, the said head also having an opening therethrough, a concaving-tool movably mounted in the head and carriage, a feeder secured to the tool and provided with a reduced bearing edge, means interposed between the feeder and the carriage for automatically throwing the tool outwardly, and a controller movable through the head and having an enlargement to contact with said bearing edge and gradually move the tool inwardly into the carriage.
10. In a machine of the class set forth, the combination of bolt-holding means, a carriage movable toward and away from said means and having an opening therethrough and a tool-holding head at one side, the said head being provided with an opening and a slot communicating with the latter, a concaving-tool movably mounted in the head and carriage, a feeder secured to the tool and provided with an arm arranged for holding the tool against rotative movement, and a controller movable through the slot of the head and having an enlargement to bear upon said arm to gradually feed the tool inwardly through the carriage.
11. In a machine of the class set forth, the combination of tool-holding means; a carriage movable toward and away from said means and having an opening therethrough and a tool-holding head at one side, the said head being provided with an opening and a slot communicating with the latter, a concaving-tool movably mounted in the head and carriage, a feeder secured to the tool and provided with an arm arranged for holding the tool against rotative movement, a controller having an enlargement to engage the arm of the feeder to gradually move the tool inwardly through the carriage, and means interposed between the feeder and the carriage for throwing the tool outwardly when released by the enlargement of the controller.
12. In a machine of the class set forth, the combination of a bolt-holding means, a carriage movable toward and away from said means and having an opening therethrough and a tool-head at one side, the said tool-head being formed with an opening, a slot communicating with said opening, and a groove in one wall of the latter, a concaving-tool movably mounted in the head and carriage, a feeder secured to the tool and provided with an arm having a spline slideable in the said groove and also formed with a reduced bearing edge, a controller passing through the slot in the head and having an enlargement to engage the said bearing edge, and means for automatically throwing the tool outwardly, when released by the controller.
13. In a machine of the class set forth, the combination of a frame having guide devices, a bolt-holding means, a carriage engaging the guide devices and provided with bolt-cutting devices, a controller passing through a portion of the carriage and engaging part of the bolt-cutting devices and having opposite screw-threaded extremities, brackets secured to a part of the guide devices and the frame and having slotted arms through which the screw-threaded extremities of the controller removably extend, and means for engaging the screw-threaded extremities of the controller for adjusting the latter in and securing it to the said brackets.
14. In a machine of the class set forth, a rotary bolt-holder, a carriage movable toward and from the same, a concaving-tool held by the carriage, a controller having a portion arranged to project said tool along a predetermined portion of the course of travel of the carriage to concave the body of the bolt, threaded cutting means on the carriage, and means for operating said threaded cutting means to thread the ends of the bolt.
15. In a bolt-cutting machine, the combination of a rotary vertical pindle, a bolt-holder operated thereby and having a socket therein opening upwardly to receive the lower end of a bolt-blank, vertical guides extending above the holding-socket, a carriage freely slideable on the guides and having a gravitational downward feed movement, means for raising the carriage, collapsible threading-dies on the carriage adapted to operate upon the blank on the downward feed movement thereof, and means for throwing the dies in and out.
16. In a stay-bolt machine, a holder for supporting and rotating a bolt-blank, a carriage freely slideable toward and from said holder and movable by gravity toward the same, a cutting-tool on the carriage, means arranged to be rendered effective by each downward movement of the carriage for moving the cutting-tool to turn the bolt-center, and thread-cutting means on the carriage arranged to cut in advance of the turning-tool and adapted in action to regulate the speed of movement of the carriage for the action of the turning-tool.
17. In a stay-bolt machine, a bolt-holding spindle, a carriage, a transversely-movable turning-tool on the carriage said spindle and carriage being relatively movable longitudinally of the spindle-axis to feed said turning-tool, thread-cutting means on the carriage arranged to cut in advance of the turning-tool, and a means arranged to be rendered effective by each longitudinal movement for moving the turning-tool transversely to turn the bolt-center.
18. In a stay-bolt machine, a bolt-holding spindle, a carriage, a transversely-movable turning-tool on the carriage, said spindle and carriage being relatively movable relatively

and longitudinally of the spindle-axis to feed the turning-tool, thread-cutting means on the carriage arranged to cut in advance of the turning-tool, and a means arranged to be rendered effective by each longitudinal movement for moving the turning-tool transversely to turn the bolt-center.

19. In a stay-bolt machine, a rotary bolt-holding spindle, a carriage movable longitudinally of the spindle-axis and having a feed motion toward said spindle, a transversely-movable turning-tool on the carriage, thread-cutting means on the carriage arranged to cut on the feed movement in advance of the turning-tool, and a means arranged to be rendered effective on each longitudinal feed movement of the carriage for moving the turning-tool to turn the bolt-center.

20. In a stay-bolt machine, a rotary bolt-holder, a carriage movable toward and from said holder, threading means on the carriage for threading the bolt upon the movement of the carriage toward the holder, a turning-

tool on the carriage arranged to act in such movement in rear of the threading means, and a stationary controller supported independent of the carriage and arranged to operate the turning-tool at a prescribed point in the path of movement thereof to turn the bolt-center.

21. In a stay-bolt machine, a bolt-holding spindle, a carriage, said spindle and carriage being relatively movable longitudinally of the spindle-axis, a transversely-movable turning-tool on the carriage, thread-cutting means on the carriage arranged to cut in advance of the turning-tool, and a stationary controller supported independent of the carriage and adapted upon each longitudinal movement to move the turning-tool transversely to turn the bolt-center.

In testimony whereof I affix my signature in presence of two witnesses:

COLUMBUS K. LASSITER.

Witnesses:

L. B. SMITH,

ROBT. W. ZIMMERMAN.
